UNITED STATES PATENT OFFICE.

OTTO L. RAABE, OF JERSEY CITY, NEW JERSEY, AND GEORGE F. READ, OF NEW YORK, N. Y., ASSIGNORS TO ROBERT HOE, OF NEW YORK, N. Y.

DELIVERY MECHANISM.

No. 857,962.

Specification of Letters Patent.

Patented June 25, 1907.

Application filed August 10, 1905. Serial No. 273,530.

To all whom it may concern:

Be it known that we, OTTO L. RAABE, a citizen of the United States, and a resident of Jersey City, county of Hudson, and State of New Jersey, and GEORGE F. READ, a citizen of the United States, and a resident of the city of New York, county of Kings, and State of New York, have invented certain new and useful Improvements in Delivery Mechanisms, fully described and represented in the following specification and the accompanying drawings, forming a part of the same.

This invention relates to certain improvements in delivery mechanisms such as are used in connection with high speed printing machines for printing newspapers or similar publications.

In the production of newspapers, the unit employed is the single wide web which after being printed and perfected is cut into sheets which carry two printed pages on one side and two printed pages on the other, these sheets being folded to produce a four page paper. Where a paper of more than four pages is desired, the number of webs is increased accordingly, it being usual to increase the width of the web, making it double, triple or quadruple, in order to make an eight, twelve, or a sixteen page paper, the web being slit and the separate webs produced by slitting being superposed and the product associated in a well-known manner.

The present development of the art makes it easily possible to produce papers consisting of four, eight, twelve or sixteen, or even more pages, either in the manner hereinbefore described, or by the collection of sheets during the delivery in a manner which is also well understood, the printing couples being provided with pairs of plates so imposed as to produce the four page sheets referred to, the web or webs running through said couples and to the superposing, associating and delivery mechanisms at the same speed.

The production of papers having a number of pages which is not an even multiple of four presents, however, more difficulty, especially where it is desired to produce papers printed from couples carrying a single set of plates.

Six page papers are now produced by providing the couples with duplicate sets of plates, the columns of the plates running around the cylinder, and these plates being arranged to print on a single web and on a

half width web. The half width web is associated with the single web and the two run together over a former. The folded product of this former is cut between the ends of successive pages, thus producing two six page papers for each revolution of the cylinders, the printing couples employed in this type of machine being usually rotary couples. If it were possible to make the cylinders small enough, a six page paper might be produced in this manner from cylinders carrying only a single set of plates. The plates would, however, have to be substantially circular so as to occupy the full circumference of the cylinder and the machine would be of little use except for the particular product for which it was designed. These practical reasons, therefore, make it substantially impossible to produce a six page paper in this manner from a single set of plates. Ten page papers are produced in the same manner from duplicate sets of plates, printing on two single webs or a slit double wide web, and a half width web, the plates being imposed with the columns running around the cylinder, and the half width web being associated with the two single webs. As has been pointed out, both these methods of producing six and ten page papers require duplicate sets of plates and double the amount of stereotyping. Furthermore, when machines capacitated to produce ten page papers are considered, and this is the kind of paper which is more often used, a machine operating according to this mode becomes too expensive to install in small offices, for the reason that the cylinders have to be made long enough to print two single webs and a half width web, or else two sets of cylinders, one printing a single web and the other a single web and a half width web, have to be used. Ordinarily, therefore, where the problem of producing ten page papers is involved, quite a different method of printing is resorted to. Rotary couples are employed, the cylinders of which carry a single set of plates with the columns running around the cylinders as before, these plates printing on a single wide web. A second set of couples is employed in conjunction with this machine which prints on a half width web, this set of couples running at half the speed of the other couples and producing two single page sheets for each revolution of the cylinders. The sheets cut from

the single wide web are collected in the usual manner and the single sheets from the half width half speed web are associated with them during collection. This method of producing ten page papers requires two sets of couples which must be arranged to run at different speeds and also makes a machine which is too large to be installed in small offices.

10 Generally speaking, the present invention has in view to produce a delivery mechanism for use in printing machines which shall be simple and economical to build, which will enable products to be produced from a single 15 sets of plates in which the sheets are not multiples of four, this being accomplished without the use of extra long cylinders and without the necessity of resorting to printing mechanisms which run at different speeds.

20 The invention further has in view the improvement of certain details of construction of delivery.

With these and other objects not specifically referred to in view, the invention consists in certain constructions and in certain parts, improvements and combinations as will be hereinafter fully described and then specifically pointed out.

Referring to the drawings—Figure 1 is a 30 diagrammatic side elevation of a printing machine containing the improved delivery mechanism. Fig. 2 is a front elevation of the delivery mechanism illustrated in Fig. 1. Fig. 3 is a plan view of the construction illustrated in Fig. 1. Fig. 4 is an enlarged detail view illustrating more particularly the construction of the cutting and folding mechanism employed, and also the specific means for delivering the sheets. Fig. 5 is a view similar to Fig. 4, illustrating a modified construction. Fig. 6 is a detail view showing the ends of the cylinders illustrated in Fig. 5, and certain features of the operating mechanism therefor. Fig. 7 is a view showing the 45 ends of the cylinders opposite those illustrated in Fig. 6, and certain details of the operating mechanism.

The specific construction which has been selected to illustrate an embodiment of the 50 invention is, in the drawings accompanying this application, shown in connection with a web printing machine of the rotary type. The machine illustrated contains two printing couples, the first couple consisting of 55 cylinders marked 1 and 2, and the second couple consisting of cylinders marked 3 and 4. The printing cylinders which are marked 2 and 3 respectively are supplied with ink by the usual mechanisms indicated at 5 and 6. 60 The web indicated at W is supplied from a web roll mounted in any suitable manner. Each of the printing cylinders, as indicated in Fig. 3, carries a single set of plates the columns of which are arranged parallel to the 65 axis of the cylinder. The specific construc-

tion illustrated is designed to produce either a four, a six, an eight, a ten, or a twelve page paper, as may be required, and the cylinders are, therefore, made long enough, as indicated in Fig. 3, so that each printing cylinder 70 may carry three pairs of plates arranged in the manner described, that is, with the columns parallel to the axis of the cylinder. As the machine is arranged in the construction illustrated, it is designed to produce ten 75 page papers. The cylinders therefore, carry at one end two pairs of plates and at the other end a single plate, the single plate occupying, of course, only one half the circumference of the cylinder. The machine is 80 shown as printing on a web which is wide enough to be cut by suitable slitters, indicated at 7, into three parts, these slitters co-operating with the usual roll 8.

In the construction illustrated, the web is 85 guided to the cylinders by means of a guide roll 9 and tapes 10, this construction being the usual one. After leaving the slitters, the three webs, which are marked W', W², W³ pass onward, their movement and direction being controlled by such devices as are 90 commonly employed for guiding and controlling webs. In the particular construction illustrated, the webs W', W³ pass under a guide roll indicated at 11, and the web W² 95 passes under a guide roll indicated at 12, this roll being lower than the guide roll 11. The web W' passes around a turner bar, indicated at 13 and over a guide roll 14. The web W² passes over a turner bar 15 and 100 around a guide roll 16, these webs, by the action of these bars and rolls, are so led as to be superposed and are associated as they pass between a pair of nipping rolls illustrated at 17. After these webs W' W² are 105 associated, either by the devices hereinbefore described, or by any other suitable devices, they are cut into sheets. The cutting devices employed may be varied in construction. In the particular construction illustrated, these webs are cut into sheets by 110 means of a pair of cutting and folding cylinders 19, 20, the cylinder 19 being mounted on a shaft 21 and the cylinder 20 on a shaft 22. The shaft 22 is provided with a driving gear 23 (see Fig. 7) and this gear is in mesh 115 with one of the gears of a train, the lower one of which is marked 24. This gear is mounted on a shaft 25 indicated in dotted lines in Fig. 1, which derives its power from 120 the couple driving mechanism. The shafts 21 and 22 are intergeared in the usual manner. In the particular construction shown, the cylinder 19 is provided with a cutting blade 26 which co-operates with a cutting 125 wood 27 mounted on the cylinder 20.

The cylinder 20 is provided with sheet or web taking devices which may be of any suitable description. In the construction shown, these sheet taking devices consist of pins 28, 130

these pins being operated from a rock lever 29 which runs at proper times on a suitable cam (not shown), and by a spring rod construction 31 also of usual form. The cylinder 20 is or may be provided with folding devices of any suitable description. In the particular construction shown, these folding devices consist of a double blade 32 mounted on a shaft 33 suitably journaled in the cylinder, this shaft being operated by a two-armed rocker 34, the bowls of which coöperate at suitable times with a cam, not shown. This double folding blade 32 tucks the sheets between a pair of rolls 35. In the particular construction shown, carrying tapes 36 are supported in part by these rolls, these carrying tapes carrying the folded sheets into position where they receive another fold by a folding blade, not shown. This blade coöperates with rolls 37 which deliver the sheets to an S-fly 38. This construction is of usual form and any other suitable construction may be substituted for it.

It will be understood that the webs W' , W^2 and W^3 are, since they are printed by the same couples, running at the same speed. The present invention contemplates, however, cutting from one of the webs, in this instance, the web W^3 , sheets which are less in size than the sheets cut from the other web or webs. In the particular construction shown, the web W^3 is shown as receiving impressions from a single page plate, while the other webs are shown as receiving impressions from a pair of page plates. It follows, therefore, that the web W^3 will, in the construction shown, as it passes to the web forwarding devices, bear single page impressions which are half the size of the two page impressions on the other webs, these single page impressions alternating with blank spaces on the web of the same size, these blank spaces appearing clearly in Fig. 3 and being marked 39. When, therefore, mechanism of the specific character illustrated is employed in carrying out the invention, it will be desirable that the apparatus for cutting the web W^3 into sheets be such as to cut and transfer the printed sheets from the web W^3 , so that they may be associated with sheets cut from the other web or webs. In the specific construction shown, after the web W^3 leaves the roll 11 before referred to it passes around a turner bar 40 and a guide roll 41. From this guide roll 41, the web W^3 passes between a pair of drawing rolls 42, and from these rolls between a pair of cylinders 43, 44. The cylinder 43 is mounted on a shaft 45 suitably journaled in the frame and the cylinder 44 is mounted on a similar shaft 46. These cylinders 43, 44 are of the same size as the cylinders 19, 20 before referred to and are driven therefrom, the shaft 22 of the cylinder 20 being provided with a gear 47 which meshes with a gear 48 on the shaft 45

of the cylinder 43. These cylinders 43, 44 are intergeared in the usual manner. These cylinders, therefore, make turn for turn with the cylinders 19, 20 before referred to. These cylinders 43, 44 are cutting cylinders. In 70 the particular construction shown, the cylinder 43 is provided with a pair of cutting blades 49, these blades coöperating with cutting woods 50 on the cylinder 44. As has been indicated, in the specific construction 75 illustrated, these cylinders 43, 44 not only cut half size sheets from the web W^3 but they transfer the printed sheets to be associated with the sheets cut from the webs W' , W^2 and they also take care of the unprinted sheets. 80 In order to accomplish this, in the particular construction shown, each of the cylinders 43, 44 is provided with sheet taking devices. While these sheet taking devices may be varied in construction, as shown the 85 cylinder 43 is provided with a set of sheet taking pins 51, these pins being operated from a rock lever 52 and a spring rod 53, as is usual. The cam for operating the rock lever 52 is indicated at 54 (see Fig. 4.) The sheet taking devices on the cylinder 44 as shown consists of a set of stationary pins 55. 90 It has been stated that the printed sheets cut from the web W^3 are half the size of the sheets cut from the webs W' , W^2 . As a matter of fact, however, they are little more than half the size, thus allowing for a slight lap for pasting. The sheets cut from the web W^3 may be associated with the sheets cut from the webs W' , W^2 either by laying their leading edges on about the fold line of the sheets from W' , W^2 , the leading edges, however, projecting sufficiently over the fold line to make a pasting lap, or they may be associated by bringing their leading edges into 100 register with the leading edges of the sheets cut from the sheets of webs W' , W^2 , in which cases the rear edges of the sheets from the web W^3 will slightly overlap the fold line of the sheets cut from the webs W' , W^2 . Constructions by which both these methods of 110 associations may be carried out are illustrated. In the construction shown in Fig. 4, the pins 28 take the sheets which have been cut from the web W^3 from the pins 51, the sheets being thus transferred from the cylinder 43 to the cylinder 20. In the rotation of the cylinder 20, the pins 28 lay the leading edges of the sheets cut from the web W^3 against the leading edges of the webs W' , W^2 , 120 as these webs are entering the nip of the cylinders 19, 20. As the cylinders 19, 20 rotate, these sheets and the webs W' , W^2 are carried around until the tail of the sheet cut from the web W^3 and the middle portion of 125 the sheets to be cut from the webs W' , W^2 arrive opposite the rolls 35. At this time, the tucking blade operates and thereafter the blade 26 severs the sheets from the webs W' , W^2 . This operation produces, in the 130

particular construction shown, a ten page paper with a single page sheet inset into the inner one of a pair of double sheets cut from the webs W' , W^2 , this product being shown 5 between the tapes 36 in Fig. 4. In the construction shown in Fig. 5, the cylinder 20 is provided with the pins 28 before described, and with an extra set of pins 57, these pins being mounted on arms 58 carried on a shaft 10 59. This shaft is operated from a rock arm 60 carrying a bowl which works on an interior cam formed on a ring 61 (see Fig. 6) secured to the main frame by brackets 62, and by a spring rod construction of the usual 15 type, indicated at 63. In the operation of this form of the construction, the leading edges of the webs W' , W^2 are taken by the pins 28 and the leading edge of the sheet cut from the web W^3 is taken from the pins 51 20 by the pins 57, the rotation of the cylinders being so timed that the leading edge of the sheet cut from the web W^3 is laid against the webs W' , W^2 at about the center of the sheets 25 to be cut from the webs W' , W^2 . In other respects the operation of the construction shown in Fig. 5 is the same as that illustrated in Fig. 4.

The unprinted sheets cut from the web W^3 30 may be led out of the machine in any suitable manner. In the particular construction shown, they are taken from the cylinder 44 by a stripper 64, this stripper being mounted on a shaft 64' which is operated by means of an arm 65, this arm being connected to a 35 cam rod 66, the lower end of which is forked and straddles a shaft 67, this shaft carrying a cam 68 which operates the rod. This shaft 67 is driven by a large gear 69 which is in mesh with a gear 69' mounted on the shaft 22 40 before referred to. The stripper directs the sheets in an unfolded condition between a pair of rolls 70 which in turn delivers them to a fly 71. This fly is mounted on a rock shaft 72 which is operated through a cam rod 45 73 from a cam 74 on the shaft 67 before referred to, and by a spring rod construction 75 of the usual type. The fly delivery is a desirable one for the reason that it delivers the unprinted sheets flat so that they may be 50 utilized for any suitable purpose after they have issued from the machine. In order, however, to avoid frequent reciprocations of the fly, it is desirable that the cylinder 44 be run as a collecting cylinder and that the 55 stripper be thrown in once in a predetermined number of revolutions of this cylinder. For this reason, the shaft 67 is geared down, as shown. The stripper, therefore, remains 60 out of operation during a number of revolutions of the cylinder 44, allowing the unprinted sheets to be collected thereon. If desired, tapes 76 or other similar devices may be employed to assist in retaining the collected sheets on the cylinder 44.

65 Curved sheet guiding brackets 77 of usual

form may, if desired, be employed in connection with the cylinder 20, and in the particular construction shown, a series of sheet guiding brackets 78 are employed between the cylinders 43, 44, these brackets forming 70 pathways for the sheets taken by these cylinders.

In the particular construction shown, the web W^3 has printed and unprinted spaces, the unprinted spaces being cut up into 75 sheets which are afterward piled by the fly 71 on a table 79. If desired, however, the cylinders 2, 3 which carry the plates for the ten page paper, may be provided with other plates which will print hand bills, posters, or 80 other commercial printing.

While the mechanism illustrated has been described particularly in connection with the production of a ten page paper, it is obvious that it can be used by making the web 85 narrower, so as to omit the web W' , to print papers of six pages. It is also apparent that by providing the cylinders with a full complement of plates, a twelve page paper can be produced. In this case, however, the 90 web W^3 would be a full printed web and instead of being led through the rolls 42, would be led over a guide 80 indicated in Fig. 2, from which guide it will be led directly between the rolls 17 and there associated with 95 the webs W' , W^2 . When the machine is used in this manner, the rolls 43, 44 might either be thrown out or allowed to run idly, as desired. While, furthermore, delivery mechanisms embodying the invention are 100 particularly adapted for use with rotary printing couples, they may be used with couples having other than rotary members.

Changes and variations may be made in the constructions by which the invention is 105 carried into effect. The invention is not, therefore, to be limited to the particular constructions herein shown and described.

What is claimed is:—

1. The combination with two pairs only 110 of printing and perfecting cylinders, of means for cutting and associating large sheets from a part of the product of said cylinders, means for cutting sheets less in size than the large sheets from the remainder of the product, means for associating a part only of said small sheets with the large sheets, means for folding said associated product, and means for directing the remainder of the small sheets unassociated 115 with the large sheets out of the machine.

2. The combination with means for forwarding a plurality of webs at the same speed, of means for cutting the webs into sheets, the sheets cut from one web being less in size than the sheets cut from the other web or webs, means for associating a part 125 of the small sheets with the large sheets and folding them therewith, and means for sending the other small sheets out of the ma- 130

chine in an unfolded condition and unassociated with large sheets.

3. In a printing machine, the combination with means for forwarding at the same speed a plurality of webs, the webs moving in a line substantially at right angles to the printed columns thereon, of means for cutting the webs into sheets, the sheets cut from one web being less in size than the sheets cut from the other web or webs, means for associating a part only of the small sheets with the large sheets and folding them therewith, and means for sending the other small sheets unassociated with large sheets out of the machine.

4. In a printing machine, the combination with means for forwarding at the same speed a plurality of webs, the webs moving in a line substantially at right angles to the printed columns thereon, of means for cutting the webs into sheets, the sheets cut from one web being less in size than the sheets cut from the other web or webs, means for associating a part only of the small sheets with the large sheets and folding them therewith, and means for sending the other small sheets out of the machine in an unfolded condition and unassociated with large sheets.

5. The combination with means for forwarding a plurality of webs at the same speed, of means for cutting the webs into sheets, the sheets cut from one web being less in size than the sheets cut from the other web or webs, means for associating a part only of the small sheets with the large sheets so that an edge of a small sheet will lie about on the fold line of a large sheet, means for folding the large sheets around the small sheets, means for collecting the unassociated small sheets, and means for directing such collected sheets out of the machine.

6. The combination with means for forwarding a plurality of webs at the same speed, of means for cutting the webs into sheets, the sheets cut from one web being less in size than the sheets cut from the other web or webs, means for associating a part only of the small sheets with the large sheets so that an edge of a small sheet will lie about on the fold line of a large sheet, means for folding the large sheets around the small sheets, means for collecting the unassociated small sheets, and a fly for delivering said collected sheets.

55 7. The combination with means for forwarding a web, said web having printed pages and blank spaces thereon, the blank spaces being substantially equal in size to the printed pages and alternating therewith, said web moving at right angles to the columns of the pages, means for slitting the web to form a plurality of webs, one of said webs containing the printed pages and blank spaces, means for cutting the blank space web into printed and blank sheets, means for

cutting the other web or webs into sheets larger in size than the printed sheets cut from the blank space web, means for associating the small printed sheets with the large printed sheets so that an edge of the small sheet lies on about the fold line of the large sheet, means for folding the large sheets about the small sheets, and means for directing the blank sheets out of the machine.

8. The combination with means for forwarding a web, said web having printed pages and blank spaces thereon, the blank spaces being substantially equal in size to the printed pages and alternating therewith, said web moving at right angles to the columns of the pages, means for slitting the web to form a plurality of webs, one of said webs containing the printed pages and blank spaces, means for cutting the blank space web into printed and blank sheets, means for cutting the other web or webs into sheets larger in size than the printed sheets cut from the blank space web, means for associating the small printed sheets with the large printed sheets so that an edge of the small sheet lies on about the fold line of the large sheet, means for folding the large sheets about the small sheets, means for collecting a number of the blank sheets, and means for delivering the collected sheets.

9. The combination with means for forwarding a web, said web having printed pages and blank spaces thereon, the blank spaces being substantially equal in size to the printed pages and alternating therewith, said web moving at right angles to the columns of the pages, means for slitting the web to form a plurality of webs, one of said webs containing the printed pages and blank spaces, means for cutting the blank space web into printed and blank sheets, means for cutting the other web or webs into sheets larger in size than the printed sheets cut from the blank space web, means for associating the small printed sheets with the large printed sheets so that an edge of the small sheet lies on about the fold line of the large sheet, means for folding the large sheets about the small sheets, means for collecting a number of the blank sheets, and a fly for delivering the collected sheets.

10. The combination with means for forwarding a three wide web, two parts of the web bearing printed sheets succeeding each other as is usual, and the other part of the web having smaller size printed sheet alternating with blank spaces substantially equal in size to the printed sheets, the web moving substantially at right angles to the columns of the printed pages, of means for dividing the web into three parts, means for superposing the full printed webs and cutting full size sheets therefrom, means for cutting the other web into printed and blank sheets, means for associating one of the smaller printed sheets with each pair of sheets cut from the other webs, the edge of the smaller

sheets being laid about on the fold line of the larger sheets, means for folding the larger sheets around the smaller sheets, and means for directing the blank sheets out of the machine.

11. The combination with means for forwarding a three wide web, two parts of the web bearing printed sheets succeeding each other as is usual, and the other part of the web having smaller size printed sheets alternating with blank spaces substantially equal in size to the printed sheets, the web moving substantially at right angles to the columns of the printed pages, of means for dividing the web into three parts, means for superposing the full printed webs and cutting full size sheets therefrom, means for cutting the other web into printed and blank sheets, means for associating one of the small printed sheets with each pair of sheets cut from the other webs, an edge of the smaller sheets being laid about on the fold line of the larger sheets, means for folding the larger sheets around the smaller sheets, and means for collecting a number of the blank sheets and delivering them from the machine.

12. The combination with means for forwarding a three wide web, two parts of the web bearing printed sheets succeeding each other as is usual, and the other part of the web having smaller size printed sheets alternating with blank spaces substantially equal in size to the printed sheets, the web moving substantially at right angles to the columns of the printed pages, of means for dividing the web into three parts, means for superposing the full printed webs and cutting full size sheets therefrom, means for cutting the other web into printed and blank sheets, means for associating one of the smaller printed sheets with each pair of sheets cut from the other webs, an edge of the smaller sheets being laid about on the fold line of the larger sheets, means for folding the larger sheets around the smaller sheets, means for collecting a number of the blank sheets, and a fly for delivering the collected sheets.

13. The combination with a pair of cutting and folding cylinders, one of said pair of cylinders having sheet retaining devices, of web directing means coöperating with said cylinders, of a second pair of cylinders provided with cutting devices, sheet retaining devices on one cylinder of said pair, said devices being arranged to take alternate sheets and deliver said sheets to the sheet retaining devices of the first pair of cylinders, means for collecting the other sheets cut by said second pair of cylinders, means for delivering the collected sheets, and web directing devices coöperating with said second pair of cylinders.

14. The combination with a pair of cutting and folding cylinders, one of said pair of cylinders having sheet retaining devices, of web

directing means coöperating with said cylinders, of a second pair of cylinders provided with cutting devices, sheet retaining devices on one cylinder of said pair, said devices being arranged to take alternate sheets and deliver said sheets to the sheet retaining devices of the first pair of cylinders with an edge of the smaller sheets lying on about the fold line of the larger sheets, means for operating the folding devices of the first pair of cylinders so as to fold the larger sheets around the smaller sheets, means for collecting the other sheets cut by said second pair of cylinders, means for delivering the collected sheets, and web directing devices coöperating with said second pair of cylinders.

15. The combination with a pair of cutting and folding cylinders, one of said cylinders having sheet retaining devices, of a pair of cutting cylinders running at the same surface speed as the other cylinders and arranged to cut sheets less in size than the sheets cut by the first pair of cylinders, sheet retaining devices on the cylinders of said second pair, said devices being arranged to take alternate sheets cut by the cylinders, means for operating the sheet retaining devices of one of the cylinders of the second pair to cause it to deliver its sheets to the sheet retaining devices of the first pair of cylinders, means for removing the sheets from the other cylinder of the second pair, means for operating said removing means once in each predetermined number of revolutions of said cylinder, and web directing means coöperating with each pair of cylinders.

16. The combination with a pair of cutting and folding cylinders, one of said cylinders having sheet retaining devices, of a pair of cutting cylinders running at the same surface speed as the other cylinders and arranged to cut sheets less in size than the sheets cut by the first pair of cylinders, sheet retaining devices on the cylinders of said second pair, said devices being arranged to take alternate sheets cut by the cylinders, means for operating the sheet retaining devices of one of the cylinders of the second pair to cause it to deliver its sheets to the sheet retaining devices of the first pair of cylinders with an edge of the smaller sheets lying on about the fold line of the larger sheets, means for operating the folding devices of the first pair of cylinders so as to fold the larger sheets around the smaller sheets, means for removing the sheets from the other cylinder of the second pair, means for operating said removing means once in each predetermined number of revolutions of said cylinder, and web directing means coöperating with each pair of cylinders.

17. The combination with a pair of cutting and folding cylinders, one of said cylinders having sheet retaining devices, of a pair of cutting cylinders running at the same surface speed as the other cylinders and arranged to

cut sheets less in size than the sheets cut by the first pair of cylinders, sheet retaining devices on the cylinders of said second pair, said devices being arranged to take alternate sheets cut by the cylinders, means for operating the sheet retaining devices of one of the cylinders of the second pair to cause it to deliver its sheets to the sheet retaining devices of the first pair of cylinders, with an edge of the smaller sheets lying on about the fold line of the larger sheets, means for operating the folding devices of the first pair of cylinders so as to fold the larger sheets around the smaller sheets, means for removing and delivering sheets from the other cylinder of said second

pair, said removing and delivering means including a stripper and a fly, means for operating said removing and delivery means once in a predetermined number of revolutions of said cylinder, and web directing means coöperating with each pair of cylinders. 20

In testimony whereof, we have hereunto set our hands in the presence of two subscribing witnesses.

OTTO L. RAABE.
